UNITED STATES PATENT OFFICE.

WILLIAM H. THORNBURG, OF GREENVILLE, ILLINOIS

HOLDBACK DEVICE.

No. 926,519.

Specification of Letters Patent.

Patented June 29, 1909.

Application filed December 18, 1908. Serial No. 468,173.

To all whom it may concern:

Be it known that I, WILLIAM H. THORNBURG, citizen of the United States, residing at Greenville, in the county of Bond and State of Illinois, have invented certain new and useful Improvements in Holdback Devices, of which the following is a specification.

The present invention relates to certain new and useful improvements in harness, and 10 more particularly to a novel hold back device which entirely eliminates the usual breeching.

The object of the invention is the provision of a device of this character which can be readily applied to a harness, which will operate in an effective manner as a hold back, and which enables a horse or other draft animal to be hitched or unhitched in a comparatively short space of time.

For a full understanding of the invention 20 and the merits thereof and also to acquire a knowledge of the details of construction and the means for effecting the result, reference is to be had to the following description and accompanying drawings, in which:

25 Figure 1 is a perspective view of a hold back device embodying the invention, Fig. 2 is a side elevation of the same, portions being broken away and shown in section, and Fig. 3 is a transverse sectional view on the line 30 3—3 of Fig. 2. Fig. 4 is a plan view of a modified form of the shaft receiving ring.

Corresponding and like parts are referred to in the following description and indicated in all the views of the drawings by the same 35 reference characters.

Referring to the drawing the numeral 1 designates the shaft of an ordinary vehicle, and 2 a plate which is secured to the shaft, preferably at the top thereof. This plate is 40 formed with a series of forwardly facing teeth 3 which constitute a rack, and also at its rear end with a stop 4. A ring 5 is slipped over the shaft, the said ring being of such a size as to pass over the teeth 3 but to engage the 45 stop 4 so that it can not be moved rearwardly beyond the plate 2. The top of the ring 5 is formed with a loop 6 and at the bottom of the ring is a similar loop 7, the said loops being disposed in a plane at right angles to the 50 plane of the ring. The upper loop 6 is designed to have the back band of the harness

connected thereto while the lower loop 7 is designed to engage the belly band. A pawl 8 is pivoted to the upper loop 6 and normally drops downwardly toward the shaft by the 55 action of gravity. This pawl is designed to engage either one of the teeth 3 of the rack or the stop 4 and serves to prevent rearward movement of the ring upon the shaft.

It will thus be obvious that I have provided an improved hold back device which obviates the necessity of providing the usual breeching and also enables the draft animal to be quickly hitched and unhitched, there being no breeching straps to be connected 65 to the shafts and the rings 5 slipping freely over the shafts when being either applied thereto or removed therefrom.

Under some conditions it may be found desirable to employ a hold back strap and the modifications shown in Fig. 4 would then be employed. It will be observed that in this modification the shaft receiving ring 5 is provided upon its inner and upper portion with a loop 9 to which the hold back 75 strap can be secured. In practice these rings 5 would be made in lefts and rights so that the said loops 9 would always be upon the inside.

Having thus described the invention what 80 is claimed as new is:

In a hold back device, the combination of a shaft, a rack provided on top of the shaft and consisting of a series of forwardly facing teeth terminating at its rear end in a relatively large stop, a ring loosely encircling the shaft and slideable thereon over the rack and having its rearward sliding movement limited by the stop, the ring being provided at points above and below the shaft with 85 outstanding loops for attachment to the harness, and a pawl pivoted to the upper loop and gravity actuated to engage any selected one of the teeth or the stop to maintain the ring in longitudinally adjusted position 90 against rearward displacement.

In testimony whereof I affix my signature in presence of two witnesses.

WILLIAM H. THORNBURG. [L. S.]
